UNITED STATES PATENT OFFICE.

THEODORE F. LEMASSENA AND JAMES STANLEY, OF NEWARK, NEW JERSEY;
SAID LEMASSENA ASSIGNOR TO LILLIAN LEMASSENA, OF SAME PLACE.

MOLD FOR HORSE-COLLARS.

SPECIFICATION forming part of Letters Patent No. 297,700, dated April 29, 1884.

Application filed November 19, 1883. (No model.)

To all whom it may concern:

Be it known that we, THEO. F. LEMASSENA and JAMES STANLEY, citizens of the United States, residing in Newark, Essex county, New Jersey, have invented certain new and useful Improvements in Molds for Horse-Collars, fully described and represented in the following specification and the accompanying drawings, forming a part of the same.

10 This invention consists in a mold for shaping horse-collars, principally such as are formed of the material described in another patent application filed by us.

In the invention referred to we form horse-collars by pasting together scraps of leather in a rough mold of suitable size, to give the article its initial form, and subsequently subject the same, after partially drying the article, to sufficient pressure in the finishing-mold to produce the ultimate desired form.

The mold described herein may be used for either a roughing or finishing mold, and its construction is designed, primarily, to form a horse-collar having a groove or crease upon 25 its edge to receive the hames, and which cannot be drawn out of the mold unless some portion of the latter be constructed to pull out of the mold with the article, or to be drawn away from the groove or crease separately.

30 The construction shown herein adapts the mold for shaping the collar, whether the same be formed of scraps or by any other method.

The essential features of the mold are an upper and lower section, embracing the rear 35 and front parts of the collar, and removable side sections adapted to form the crease for the application of the hames to the edge of the collar. The side sections may be made apart from the top and bottom sections, if preferred, or as a loose rib inserted in the bottom section.

In the drawings, Figure 1 is a plan of the bottom section. Fig. 2 is an edge view of the same; Fig. 3, an edge view of the upper section; Fig. 4, a section of the closed mold on line $x-x$ in Fig. 1. Fig. 5 is a plan of the loose side sections detached from the mold and viewed from the upper side; and Fig. 6 is an edge view of the interior of one of such sections.

50 The drawings show the parts provided with

lugs and guide-pins by which they are secured in their closed position, A being the bottom section; B, the top section; C, the side sections when loose; C', the same when formed as an inserted rib; D, the guide-lugs, and E the 55 guide-pins. The bottom section is shown as a plate provided with a raised rib, a , adapted to fit inside the collar and form its inner rounded edge, commonly called the "back" of the collar. That part of the rib which thus 60 shapes the collar is shown at the ends of Fig. 2, and a' indicates a part of the bottom bed or flange where the convex side of the collar slightly penetrates the same and forms the hollow indicated at a' in Fig. 1. The top section is shown in Fig. 3 shaped to fit that side of the collar which is pressed toward the horse's neck, commonly called the "front" of the collar, and is formed with a similar shaping-flange, b , a continuous hollow being formed in the 70 flange of the same at b' to shape the face of the collar. The side sections are shown in the upper side of Fig. 4, and also in Figs. 5 and 6, as adapted to shape the greater part of the outside of the collar, and to form the crease 75 in which the hames are fitted and secured when the collar is in use. The hollow shown at c in Fig. 6 is continuous with the hollow a' in the bed-plate in the bottom section when the mold is closed, as is clearly indicated at the 80 upper side of Fig. 4, and by the running out of the lines at c' in Fig. 6 and at the lower side of Fig. 4. The top and bottom sections are shown in contact at both their inner and outer edges at d , and the inserted rib C' is 85 shown merely sufficiently diminished to form the required crease in the collar and to draw out of the bottom section with the collar when the halves of the mold are separated to remove the same.

When used for finishing a collar previously formed, the collar is applied to the lower part of the mold A, the sides C pressed inward upon it, the pins E inserted in the lugs D, and the top section B is then placed upon the pins 95 and forced down upon the collar by the application of any suitable press. If required, the side sections may be subjected to similar pressure to bring them into the position where the pins may be inserted, the top section being 100

generally applied last to produce the final shape by its pressure upon the larger part of the collar. Pins without heads may be used; but when made with heads to facilitate removal, the pins are withdrawn to apply each piece A B C. When the collar is formed in the mold, the bottom and side sections are held together by the pins and the material from which the collar is built up is held inside the mold until the rough shape is sufficiently produced. The application of the upper section with suitable pressure then suffices to shape the collar in the desired manner.

Having thus described the nature of our invention, it will be seen that the essential feature is the provision of the loose section for shaping the hame-crease, the same being adapted to pull out of the crease independently of the upper and lower sections, the crease preventing the removal of such loose sections in the same direction as either the top or bottom pieces.

We are fully aware that molds made in sections are not new, and do not therefore claim such an invention, but we are not aware that any mold has been constructed with the same features as ours and adapted to form a horse-collar in the manner described, the peculiarity of our invention being that the top and bottom sections are each made in one piece, while the side sections require to be parted longitudinally, as at e in Fig. 5, that they may be drawn off of the collar sidewise to remove them from the crease.

We are also aware of United States Patent No. 52,826, of 1866, for pressing one side of a horse-collar at once at the hame-crease; but as such construction could not be used in molding an entire collar in such a process as we employ, we entirely disclaim the same, and claim our own construction as follows:

1. The combination, in a horse-collar mold, of the top and bottom sections, B A, each made in one piece to fit the front and back of the collar, as described, and the side sections, formed in two pieces and fitted to the hame-crease, substantially as and for the purpose set forth.

2. In a horse-collar mold, the top and bottom sections, fitted to one another upon the inner side of the collar, and provided with an open space at the outer side along the line of the hame-crease, in combination with the loose sections C, fitted to such open space for shaping the hame-crease, and held in place by the pins E, the whole arranged and operated as and for the purpose set forth.

In testimony whereof we have hereunto set our hands in the presence of two subscribing witnesses.

THEO. F. LEMASSENA.
JAMES STANLEY.
